[57] CLAIM

The ornamental design for a combined table top trash
cannister and condiment tray, as shown and described.

DESCRIPTION

FIG. 1 is a top, front, left side perspective view of a
combined table top trash canister and condiment tray
showing my new design;

FIG. 2 is a central cross-sectional view thereof;

FIG. 3 is a bottom plan view thereof;

FIG. 4 is a right side elevational view thereof;
The undisclosed rear view is a mirror image of the
front.
